COMBINED THERMOSTAT AND AUTOMATIC PILOT CONTROL

Michael J. Caparone, Arcadia, and Charles M. Vaughn, Santa Monica, Calif., assignors to Robertshaw-Fulton Controls Company, Greensburg, Pa., a corporation of Delaware

Application July 31, 1951, Serial No. 239,554

5 Claims. (Cl. 236—21)

1

This invention relates to combination controls for gaseous fuel burners wherein the temperature controlling device and the pilot cut-off both operate upon a single control valve.

The present invention is particularly adapted, although not limited, for use with gas burning water heaters and the like wherein water temperatures are controlled within precise limits.

The thermostatic device which is responsive to the water temperature is preferably of the rod-and-tube type having temperature adjustment means located on the control body for ready access by the user. The automatic pilot control in this embodiment includes an expansible thermal element of the mercury vapor pressure type responsive to the flame of the pilot burner.

Since provision may be made for complete shut-off of fuel to both the main and pilot burners under automatic control, a separate pilot valve can be provided for conjoint operation to closed position with the main burner valve. Operation of such a pilot valve to open position can conveniently be effected by a control handle on the body adjacent the temperature adjustment means. An interlock between the main gas cock and the pilot valve will permit operation of the latter to open position only when the gas cock is in the "pilot" position and is thus positioned for preventing flow of fuel to the main burner valve. Thereafter, the pilot valve is maintained opened by operation of the automatic pilot control whenever the pilot burner is producing a flame for heating the expansible thermal element.

The invention includes a pivoted lever member operably engageable with the main burner valve which is biased toward closed position and is operable toward open position by the thermostatic device. The lever member is engageable by an actuating member biased for moving it to an active position for holding the main valve closed irrespective of the thermostatic device. Manually operable means are effective for overcoming the bias of the actuating member for movement of the lever member to an inactive position and freeing the main valve for an opening operation. Means are also provided for operating the pilot valve to open position while the lever member is in the inactive position. The expansible thermal element responsive to a flame at the pilot burner serves to maintain the lever member in said inactive position upon release of the manually operable means.

The device provides safe lighting since the manually operable means is effective for holding the pilot valve open only when the interlock is

2

effective. Moreover, a complete shut-off of fuel to both main and pilot burners occurs upon extinguishment of the pilot burner flame. These objects are accomplished with a fail-safe type of unit which prevents leakage of gas under abnormal conditions of damage to the automatic pilot control.

With these and other objects and advantages in view, a preferred embodiment of the invention is illustrated in the accompanying drawings, wherein:

Fig. 1 is a plan view of the control device;

Fig. 2 is a longitudinal section on an enlarged scale taken on the line II—II of Fig. 1;

Fig. 3 is a cross-section on an enlarged scale taken on the line III—III of Fig. 1, but revolved 90°;

Fig. 4 is a cross-section taken on the line IV—IV of Fig. 3;

Fig. 5 is a partial section taken on the line V—V of Fig. 3;

Fig. 6 is a section on an enlarged scale taken on the line VI—VI of Fig. 2;

Fig. 7 is a plan view of a detail, and

Fig. 8 is an elevation of the detail shown in Fig. 7.

Main shut-off cock

Referring more particularly to the drawings, 30 the control device comprises a casing 10 provided at one end with a lateral inlet opening 12 for fuel and at the other end with an outlet opening 14 for the fuel. A main fuel passage 16 through the casing 10 provides communication between the inlet 12 and the outlet 14. As is customary in such devices, suitable pipe connections may be provided at the inlet 12 and the outlet 14 to convey fuel through the passage 16 to a main burner (not shown) of the appliance upon which 40 the control is to be used.

The passage of fuel between the inlet 12 and the outlet 14 is under control of a main shut-off cock 18. The shut-off cock 18 is provided with an angular port 20 which is movable upon manual rotation of the cock 18 by a knob 22 to open and close communication through the passage 16 between the inlet 12 and the outlet 14. Preferably, the knob 22 carries the usual indicia (not shown) for the "on," "off" and "pilot" positions 45 of the main shut-off cock 18 which are adapted to register selectively with a pointer 24 carried by a stop plate 25 secured to the casing 10 in an appropriate location.

The knob 22 is also adapted for axial movement relative to the cock 18 for a purpose ap-

parent hereinafter. As shown more clearly in Figs. 6, 7 and 8, the knob 22 is provided on its underside with a substantially annular recess 28 which however, is interrupted by an un-recessed or land portion 28 and a cam portion 30 which lies opposite the indicia "pilot." An arcuate adjustable stop element 32 is secured to the underside of the knob 22 by a screw 34 which is accessible from the exterior of the knob 22. A second stop element 36 projects from the stop plate 25 into the recess 28.

The structure described serves to limit the rotation of the knob 22 to an arc of approximately 180° between the "off" and "on" positions. Thus, when the knob 22 is rotated to the "off" position, the land portion 28 abuts the stop element 36 and further rotation is prevented. Likewise, when the knob 22 is rotated to the "on" position then the adjustable stop 32 abuts the stop 36. It will be apparent that the position of the stop 32 can be altered by loosening the screw 34, setting the stop 32 to the desired position and then tightening the screw 34.

A plunger 38 projects from the casing 10 underneath the knob 22 for alignment with the cam element 30 in the "pilot" position. Thus, when the knob 22 is rotated to the "pilot" position and moved axially relative to the shut-off cock 18 then the cam element 30 will engage the plunger 38 and move it inwardly of the casing 10. Movement of the plunger 38 outwardly of the casing 10 is limited by engagement of a collar 40 formed on the plunger 38 with the interior bottom wall of a cap nut 42 on the casing 10 and through which the plunger 38 projects. A coil spring 44 serves to bias the plunger 38 outwardly of the casing 10, but such movement is limited as described.

Pilot valve

As shown more clearly in Figs. 3 and 5, the casing 10 is provided with an integral hollow boss 46 disposed on one side of the shut-off cock 18 and provided with a hollow filter cartridge 48 for the pilot fuel. The bottom wall of the filter cartridge 48 is suitably sealed, as at 50, in fluid-tight connection with the bottom wall of the hollow boss 46. The outer wall of the cartridge 48 is, however, spaced from the inner wall of the boss 46 to provide for passage of fuel therebetween. To this end, a passage 52 is formed in the casing 10 for communication at one end with an arcuate groove 54 in the side wall of the shut-off cock 18 forming an extension of the port 20 therethrough. The groove 54 affords communication between the port 20 and the passage 52 when the shut-off cock is in the "on" position and fuel is passing directly from the port 20 to the main fuel passage 16.

The opposite end of the passage 52 communicates with the hollow boss 46 adjacent the side wall of the filter cartridge 48 which thereby receives fuel in its upper end to be filtered and emitted from the lower end thereof adjacent the seal 50. A pilot passage 56 formed in the boss 46 communicates at one end with the lower end of the filter cartridge 48 and at the opposite end with a pilot valve chamber 58 formed in the casing 10. A pilot valve member 60 is mounted in the chamber 58 and is reciprocable on an axis substantially normal with that of the plunger 38 to open and close a passage through a pilot valve seat member 62 which is supported in the chamber 58.

A closure cap 64 provides access to the valve member 60 and also forms a seat for one end of a

coil spring 66 serving to bias the valve member 60 toward its seat 62. An outlet passage 68 communicates with the passage in the valve seat member 62 and thus receives a supply of fuel from the inlet passage 56 when the valve member 60 is in open position. The opposite or outlet end of the passage 68 terminates in a suitable connection 70 for a pilot conduit for supplying fuel to a pilot burner (not shown). The usual adjusting means 72 is provided in the passage 68 for flow of fuel to the pilot burner.

Movement of the pilot valve member 60 between open and closed positions is effected by operation of a pilot valve stem 74 which projects through the passage in the pilot valve seat member 62 and is suitably fluted or noncircular to permit passage of fuel thereby. The usual sealing diaphragm 76 is provided for the operating end of the valve stem 74 to prevent leakage of fuel from the chamber 58. An operating head 78 is carried on the valve stem 74 on the opposite side of the sealing diaphragm 76 therefrom to provide convenient means for moving the valve member 60 to open position when desired.

Control valve mechanism

As shown more clearly in Fig. 2, an annular main valve seat member 80 is formed in the casing 10 in position to intersect the passage of fuel from the inlet 12 to the outlet 14 through the main fuel passage 16. An axial hollow boss 82 is formed within the annular valve seat 80 and provides a bearing for a main valve stem 84 which is reciprocable therein. A valve stem 84 is axially bored to accommodate an override mechanism comprising a plunger 86 and an override spring 88. The plunger 86 is biased outwardly of the valve stem 84 by the spring 88, but such relative movement is limited by a stop in the form of a bushing 90 which engages a collar 92 formed on the plunger 86. A disc-type main valve member 94 is mounted on the valve stem 84 for axial reciprocable movement therewith between open and closed positions relative to the valve seat 80 as will be described more fully hereinafter.

The axial hollow boss 82 forms one wall of a chamber 100 in the casing 10 which houses a snap-action means of conventional form comprising clicker mechanism 102 and an annular thrust element 104 for operating the valve member 94 to open position. The clicker mechanism 102 operatively engages the plunger 86 of the override mechanism which normally acts as a solid unit as hereinafter described. The thrust element 104 carries a thrust button 106 which projects through a sealing ring 108 forming an opposite wall for the chamber 100.

Temperature regulation

Thermally responsive means for operating the valve member 94 through the clicker disc mechanism 102-106 is carried by a thermostat housing 110 which is secured to the exterior of the casing 10 adjacent the thrust button 106. The housing 110 may be of conventional form for securing the casing 10 to the tank of the water heater. The usual rod-and-tube thermally responsive element 112-114 projects from the housing 110 into the tank of the water heater and, as is customary in such devices, the rod 112 has a relatively low coefficient of expansion while the tube 114 has a higher coefficient of expansion. The differential under the influence of the heat of the water in the tank causes the rod element 112 to move outwardly of the casing 10.

The rod element 112 projects toward the thrust button 106 on one side thereof and engages a connecting lever 116 having an operating end supported on the thrust button 106. The opposite end of the lever 116 is engaged by an adjusting screw 118 which extends through the casing 10 on an axis substantially parallel with that of the valve member 94. An adjusting knob 120 is carried on the adjusting screw 118 exteriorly of the casing 10 for setting the temperature to be maintained by the rod-and-tube element 112, 114. Both the gas cock knob 22 and the temperature adjusting knob 120 are located on the front face of the casing 10 for convenient access by the user. Yieldable means in the form of a leaf spring 122 is carried by the thrust button 106 for operative engagement with the lever 116 to maintain it in engagement with the thrust button 106 and the adjusting screw 118 respectively.

Automatic pilot control

The vapor-pressure type automatic pilot control of this invention is adapted to render the rod-and-tube element 112, 114 ineffective for opening the valve member 94 unless the pilot burner of the appliance is producing a flame. The automatic pilot control comprises an actuating device including a bulb element 123, a capillary tube 124 and a diaphragm unit 126 as is customary in such devices. As shown more clearly in Fig. 3, the device is adjustably connected to the casing 10 by the provision of a bushing 128 threaded into a hollow boss 132 formed on the casing 10. An internally threaded sleeve 129 is slidably mounted in the bushing 128 to abut a shoulder 131 on the bushing 128 and engage a suitably threaded connection 130 secured to the diaphragm unit 126. The hollow boss 132 extends at an angle to the main shut-off cock 18 on the opposite side thereof from the pilot valve opening 58. Provision against leakage of fuel through the boss 132 is made by a packing 134 which is compressed into engagement with the threaded bushing 128 by a packing nut 136 through which the capillary tube 124 extends. The bulb element 123 contains a quantity of mercury which becomes vaporized upon the bulb element 123 being sufficiently heated and serves to actuate the diaphragm unit 126 by expansion thereof. The diaphragm unit 126 projects into a chamber 138 communicating with the chamber 16 opposite the projection of the plunger 38 therein.

Means are employed for transmitting the movement of the diaphragm unit 126 for maintaining the valve member 94 in closed position irrespective of the rod-and-tube element 112, 114. To this end, an angular lever member 140 is pivoted intermediate its ends on a bracket 142 projecting from the casing 10 into the passage 16. The lever member 140 carries an adjusting screw 144 at one end which is operatively engageable with the valve stem 84. A coil spring 146 serves to bias the lever member 140 and the valve member 94 apart. However, the lever member 140 is adapted to be maintained in an active position with the adjusting screw 144 in engagement with the valve stem 84 by actuating means which are effective upon the opposite end of the lever 140.

The actuating means include a plunger 148 which extends from the chamber 138 into engagement with the opposite end of the lever 140. The plunger 148 is reciprocable in a sup-

port member 150 which is secured in the chamber 138 by a threaded cap member 152 mounted on the casing 10. Biasing means for urging the plunger 148 toward the lever 140 takes the form of a coil spring 154 which is operative between the cap member 152 and a suitably recessed nut 156 carried on the plunger 148 for slidable movement in the support member 150. The threaded end of the plunger 148 is provided with a screw driver slot to facilitate adjustment of the nut 156 thereon. A yieldable disc 158 may be interposed between the end cap member 152 and the support member 150 to provide a yieldable mounting for the latter.

The movement of the diaphragm unit 126 is transmitted to the plunger 148 by detent means in the form of a bell-crank 160 which is pivoted on the support member 150 for this purpose. One end of the bell-crank 160 engages with the diaphragm unit 126 while the opposite end is apertured to extend around the plunger 148 into operative engagement with the nut 156 carried thereon. It will be apparent that the spring 154 tends to rotate the bell-crank 160 clockwise as viewed in Fig. 3 and maintains it in operative engagement with the diaphragm unit 126.

The end of the lever member 140 engageable by the plunger 148 extends therebeyond and is operatively engageable on the opposite side thereof by the manually operable plunger 38. A projection 161 extends substantially normal to this end of the lever 140 for operative engagement with the operating head 78 of the pilot valve member 60.

Operation

The control device is shown in the drawings as in the normal running condition with both the pilot valve member 60 and the main valve member 94 in open position. The control device is placed in such condition by manual operation when the knob 22 is rotated to the "pilot" position and pushed in axially to engage the plunger 38 with the cam element 39 on the underside of the knob 22. The resulting inward movement of the plunger 38 serves to rotate the lever member 140 clockwise, as viewed in Fig. 2, about the bracket 142 on which it is pivoted. The projection 161 on the lever 140 engages the operating head 78 and moves the pilot valve member 60 to open position.

Fuel now flows from the inlet 12, angular port 20 in the shut-off cock 18, passage 52, hollow boss 46, filter cartridge 48, passage 56, pilot valve seat 62, passage 68, and through the connection 70 for the pilot burner. Since the angular port 20 in the main shut-off cock 18 is at this time out of alignment with the opening to the passage 16, no flow of fuel to the main outlet 14 can occur irrespective of whether the rod-and-tube element 112, 114 is in condition for opening the main valve member 94.

The fuel flowing from the pilot burner is now ignited manually while the knob 22 remains depressed. The pilot flame heats the bulb 123 which is located adjacent to the pilot burner and vaporizes the mercury contained in the bulb 123. The resulting movement of the diaphragm unit 126 serves to rotate the bell-crank 160 counterclockwise about its pivot as viewed in Fig. 3. Thus, the opposite end of the bell-crank 160 moves into engagement with the nut 156 and serves to hold the coil spring 154 compressed.

Upon release of manual pressure on the knob 22 the plunger 38 will return to its outwardly pro-

jected position. Since the coil spring 154 of the lever actuating means is held compressed by the greater force exerted by the diaphragm unit 126, the return movement of the plunger 38 is unaccompanied by counterclockwise movement of the lever member 140 as viewed in Fig. 2. Due to this lack of movement of the lever 140, the pilot valve member 60 remains in open position with the projection 161 of the lever member 140 in engagement with the operating head 78.

The knob 22 may now be rotated to the "on" position for supplying fuel from the inlet 12 through the angular port 28 to the passage 16 in the casing 10 as well as continuing the supply to the pilot passage 52 through the arcuate groove 54. It may be assumed that the rod element 112 of the rod-and-tube thermally responsive device 112, 114 is in an advanced position relative to the thrust button 106 as the water in the tank is still cold and the tube element 114 is contracted. Consequently, the end of the connecting lever 116 in engagement with the thrust button 106 is moved by the rod element 112 in a counterclockwise direction as viewed in Fig. 2 and about the end of the adjusting screw 118 as a fulcrum. Such movement of the thrust button 106 causes the clicker mechanism 102, 104 to snap over and actuate the valve member 94 to open position. Since the lever member 140 is in its inactive position, such opening movement of the valve member 94 is not interfered with and the device is placed in normal running condition as shown in the drawings.

As the water in the tank increases in temperature, depending on the temperature set by the temperature adjusting knob 120, then the rod element 112 will be retracted away from the casing 10 and the force exerted by the connecting lever 116 on the thrust button 106 will cease. Thus, the main valve member 94 will move under bias of the spring 146 toward closed position relative to the valve seat 80 to shut-off flow of fuel through the outlet 14 to the main burner. Such operation of the valve member 94 between open and closed positions will continue as necessary to maintain the temperature set by the temperature adjusting knob 120.

Should the flame at the pilot burner become extinguished then the bulb element 123 will become cooled allowing the diaphragm unit 126 to contract. The actuating means for the lever member 140 is now free to operate under bias of the coil spring 154. Consequently, the plunger 148 will rotate the lever member 140 counterclockwise, as viewed in Fig. 2, to its active position serving to close the main valve member 94 and the pilot valve member 60 under bias of the coil springs 146 and 66 respectively. Thus, a complete shut-off of fuel to both the pilot outlet 70 and the main burner outlet 14 occurs upon operation of the automatic pilot control.

The main valve member 94 will remain closed irrespective of the cooling of the water in the tank and the resulting movement of the rod element 112 inwardly of the casing 10. Thus, should such movement of the rod element 112 occur under these conditions, then the clicker mechanism 102, 104 will snap over without any damage occurring due to operation of the override mechanism. In this operation the spring 88 becomes compressed by movement of the override plunger 86 relative to the valve stem 84 instead of this device operating as a solid unit as in normal operation.

It is apparent that should a leak develop in the

actuating element comprising bulb 123, capillary tube 124, and diaphragm unit 126 during normal running conditions, then the actuating element can no longer exert a force tending to rotate the bell-crank 160 to a position for holding the spring 154 compressed. Consequently, a complete shut-off of fuel will occur as in the case of operation of the automatic pilot control upon extinguishment of the flame at the pilot burner. This fail-safe feature is utilized in conjunction with the automatic pilot control and the provision for safe lighting to afford complete safety control in devices of the described character.

It will be understood that many changes may be made in the details of the construction and arrangement of parts without departing from the scope of this invention as defined in the appended claims.

We claim:

1. A combined temperature and automatic pilot control comprising in combination, main and auxiliary valve means biased toward closed position, a first thermally responsive means for operating said main valve means toward open position, a pivoted lever member operably engageable at one end with said main valve means, an actuating member engageable with the opposite end of said lever member, means for biasing said actuating member for moving said lever member to an active position for holding said main valve means closed irrespective of said first thermally responsive means, manually operable means engageable with one of said members for overcoming said biasing means for movement of said lever member to an inactive position and freeing said main valve means for said opening operation, means carried by one of said members for operating said auxiliary valve means toward open position in said inactive position of said lever member, detent means cooperable with said actuating member, said detent means having a first position wherein said actuating member is restrained from movement under said bias and a second position wherein said actuating member is free to act under said bias, and a second thermally responsive means including an expansible diaphragm unit for moving said detent means to said first position in one thermal condition thereof and to said second position in another thermal condition thereof.

2. A combined temperature and automatic pilot control as claimed in claim 1 wherein said actuating member comprises a plunger engageable with one side of said lever member, said manually operable means including a second plunger engageable with the opposite side of said lever member.

3. A combined temperature and automatic pilot control comprising in combination, main and auxiliary valve means biased toward closed position, a first thermally responsive means for operating said main valve means toward open position, a pivoted lever member operably engageable at one end with said main valve means, an actuating member engageable with the opposite end of said lever member, means for biasing said actuating member for moving said lever member to an active position for holding said main valve means closed irrespective of said first thermally responsive means, manually operable means engageable with one of said members for overcoming said biasing means for movement of said lever member to an inactive position and freeing said main valve means for said opening operation, means carried by one of said members for operating said

auxiliary valve means toward open position in said inactive position of said lever member, a second thermally responsive means including an expansible diaphragm unit positioned adjacent said actuating member, and a second lever member operatively engageable with said actuating member, said second lever member having a first position wherein said actuating member is restrained from movement under said bias and a second position wherein said actuating member is free to act under said bias, said diaphragm unit being operatively engageable with said second lever member for moving the same between said first and second positions in response to variations in a temperature condition sensed by said second thermally responsive means.

4. A combined temperature and automatic pilot control as claimed in claim 3 wherein said actuating member comprises a plunger engageable with one side of said lever member, said manually operable means including a second plunger engageable with the opposite side of said lever member.

5. A combined temperature and automatic pilot control comprising in combination, a casing having an inlet and an outlet for fluid, a rotatable valve member controlling a passage for fluid between said inlet and outlet, pilot valve means controlling a passage for fluid from said inlet under control of said rotatable valve member and being biased to a closed position, an axially reciprocable valve means also controlling the passage of fluid between said inlet and outlet and being biased to a closed position, a first thermally responsive means for operating said main valve means toward open position, lever means operably engageable at one end with said reciprocable valve

means, a first actuating member engageable with the opposite end of said lever means, means for biasing said first actuating member for moving said lever means to an active position for holding said reciprocable valve means closed irrespective of said first thermally responsive means, a second actuating member engageable with said opposite end of said lever means for overcoming said biasing means for movement of said lever means to an inactive position and freeing said reciprocable valve means for said opening operation, means effective in one position of said rotatable valve member for manual operation of said second actuating member, means carried by said lever means for operating said pilot valve means toward open position in said inactive position of said lever means, detent means having a first position for holding said first actuating member against said bias and a second position for freeing said first actuating member for movement under said bias, and a second thermally responsive means including an expansible diaphragm unit operatively engageable with said detent means for moving the same to said first position in one thermal condition thereof and to said second position in another thermal condition thereof.
